COAT

William Graber, Brooklyn, N. Y.

Application August 1, 1939, Serial No. 287,682

1 Claim. (Cl. 2—98)

The purpose of this invention is to provide a woman's coat which will be convertible for use in different seasons. The invention is adaptable more especially to cloth coats, the material for which is usable in different seasons. Such coats may suitably be fur trimmed for winter, while a fairly voluminous cloth collar will serve for fall and spring, and in the warmer season such a coat may be substantially collarless.

This invention provides means for readily converting the coat to any one of the styles mentioned. Preferably the coat has a permanent, narrow, standing cloth collar which extends entirely around the neck and may be buttoned in front or left open and folded back with the lapels. In addition it has means to secure other collars removably about the rear part of the permanent collar at its base, and a suitable flap is provided to cover the securing means when not in use or to overlie the auxiliary collars. The flap means are of the proper width to extend just up to the top of the permanent collar when the auxiliary collars are raised and folded so as to bring them together underneath the chin. The securing means will preferably be of the "Zipper" type. If desired the lining may be made readily removable to make the weight as well as style conformable to the season.

I shall now describe the invention by reference to the constructions illustrated in the accompanying drawings, and shall thereafter point out my invention in the claim.

Fig. 1 is a side view of the top part of a coat embodying my invention and shown without auxiliary collar and with the coat open in front.

Fig. 2 is a similar view showing an intermediate weight collar attached.

Fig. 3 is a similar view showing the same parts as in Fig. 2 but with the permanent and auxiliary collars buttoned in front.

Fig. 4 is a section on line 4—4 of Fig. 3.

Fig. 5 is a front view of the coat in condition shown in Fig. 3.

Fig. 6 is a view similar to Fig. 5 but with a fur trimmed collar in place of the cloth collar, and with the permanent collar closed and the auxiliary collar open.

Fig. 7 is a section similar to Fig. 4 of the parts shown in Fig. 6.

At the neck of the coat between the body 1 and lining 2 there is sewed by stitching 3 a strip of cloth folded double and forming a narrow standing collar 4 with a lateral reverse fold forming a flap 5 which joins the collar at its base and extends around the back of the collar from shoulder to shoulder. Stitching 6 through the four layers of the fold at the base of the flap secures the fold and allows the flap to be turned up or down. Underneath the flap and secured in the

construction shown by the stitching 3 is a "Zipper" tape 7. As shown in Fig. 1 this "Zipper" is covered by the flap 5 when the flap is down.

The standing collar 4 extends around the entire neck of the coat and may be buttoned over in military fashion as shown in Figs. 3, 5 and 6, for example, or may be left open as shown in Figs. 1 and 2, for example. In the latter case the front ends may be folded back with the lapels, button hole 8 buttoning on button 9 and button hole 10 buttoning on button 11. In the former case the button hole 10 buttons on button 12 as shown best in Fig. 6. Under either of these circumstances the flap 5 will lie down as indicated by the broken lines in Fig. 1, the flap being shown raised at the end in this figure as well as in Fig. 2 to disclose the Zipper.

For the intermediate seasons a full fashioned cloth collar 13 is provided of the proper size and shape and equipped with a cooperative "Zipper" tape 14a (Fig. 4) for attachment to the Zipper 7. This auxiliary collar may then be worn down and open as shown in Fig. 2 or it may be turned up and fastened in front, as shown in Figs. 3, 4 and 5. In the former case the permanent collar 4 and the lapels may be open and buttoned back as above described, or they may be buttoned at the neck, the flap 5 in both instances overlying the top of the collar 13. In the latter case the flap is turned up against the permanent collar and both it and the permanent collar are concealed by the auxiliary collar.

For winter the collar 13 may be replaced by a fur trimmed collar 14 which has a skin 14a sewed on to a cloth lining 14b, the latter being provided at its top edge with a cooperative "Zipper" tape for attachment to the "Zipper" 7. This auxiliary collar is shown open in Figs. 6 and 7 but it may be folded and closed around the neck similar to the collar 13. When open the permanent collar may be closed as shown in Fig. 6, or it may be open and the lapels folded back as above described.

Modifications in the construction shown in the drawings and above described within the principle and scope of the invention as defined in the appended claim will readily occur to those skilled in the art.

I claim:

50 A woman's coat comprising a strip folded double and forming an upright collar permanently secured to the neck and including around its rear part an integral fold forming a flap joining the collar at its outside bottom edge and positionable either up or down, a "Zipper" tape secured about the said rear part below the base of and underneath said flap, and a separate collar shaped and proportioned to fit the coat and having a cooperative Zipper tape.

WILLIAM GRABER.
